UNITED STATES PATENT OFFICE.

JOSEPH MATUSHAK, OF GARFIELD, NEW JERSEY.

DOLL CARRIAGE.

Application filed June 23, 1924. Serial No. 721,766.

To all whom it may concern:

Be it known that I, JOSEPH MATUSHAK, a citizen of the United States, residing at Garfield, in the county of Bergen and State of New Jersey, have invented certain new and useful Improvements in Doll Carriages, of which the following is a specification.

My invention relates to a toy in the form of a doll carriage provided with moving 10 manikins or other figures and cradles actuated by the travel of the carriage.

The carriage has a central revoluble platform in imitation of a circus provided with manikins or figures representing horses or 15 other animals attached to the upper side of said platform.

At each end of the carriage is suspended a cradle to the bottom of which is attached a heavy weight, the inertia of which causes 20 the cradles to rock when the carriage is pushed along a floor, while the circus or revolving platform is actuated from the wheel axle.

In the accompanying drawings, one embodiment of the invention is illustrated, 25 and—

Figure 1 is a perspective view of the doll carriage;

Figure 2 is a top plan view partly in section, and

Figure 3 is a vertical section along line 3—3 of Fig. 2.

In the drawings, reference numeral 10 represents a carriage consisting of two side walls 11 and two end walls 12, as well as a bottom 13 forming a box-shaped structure open at the top. This box is carried on a frame having side runners 14 and end runners 15. The side runners 14 are provided 35 with bearings 16 for the front wheel axle and the rear axle 17 to which the rear wheels 18 are rigidly secured is carried in longitudinal slots 19 provided in said side runners 14. A pair of adjusting rods 20 grip around 40 the rear axle 17 and extend rearwardly through the transverse or end runner 15 and carry nuts 21 threaded on the ends of the rods 20. By this arrangement it is possible to adjust the rear axle 17 in longitudinal direction of the frame.

In substantially the center part of the carriage 10 is mounted an upright spindle 22 which runs through the bottom 13 and is supported on a thrust bearing 23 secured on 50 the under side of the frame. Between the bottom 13 and this bearing is mounted a

sheave 24 for a rubber or leather belt 25 engaging a pulley 26 secured on the rear axle 17. It is evident that the pulley 26 runs in a vertical plane while the sheave 24 rotates in a horizontal plane and that the belt 25 must accordingly be twisted a quarter turn. The adjusting rods 20 with the nuts 21 are supplied to give the proper tension to the belt 25 and may be adjusted from time 65 to time in case the belt should be found to be slack and not properly operating the sheave 24 and spindle 22.

Above the bottom 13 of the carriage a cage 27 is secured on the spindle 22 and adapted to 70 revolve therewith. The cage has a roof 28 and a floor 29 connected by means of uprights 30. The uprights are narrow so that figures 31 can be clearly seen between them when the cage 27 rotates. These figures are 75 secured to the floor 29 as indicated in Figures 1 and 3 of the drawings.

Above the cage 27 is furnished a bridge 32 connecting the side walls 11 and constituting an upper bearing for the spindle 22. 80 The spindle preferably projects slightly above the bridge 32 and is furnished with a crown 39.

Near each end of the carriage a cradle 33 is mounted upon studs 34 secured in the 85 side walls 11 and permitting free oscillation of the cradle. Under the bottom 35 of each cradle is attached a heavy weight 36 and it will be clearly understood that the inertia of the weights will cause the cradles to oscillate whenever the carriage is pushed or pulled along the floor. The oscillation of the cradles will thus be fairly irregular and entirely independent of the circus cage 27 which is directly actuated by the rotation 95 of the rear axle 17 when the carriage is moved along the floor.

At the rear end of the carriage a handle 37 is secured to the side runners 14 of the frame, while the upper end of the handle 100 37 is furnished with a hand grip 38 for operating the device.

In the middle of each side wall 11 is furnished a circular window 40 through which the figures in the cage can be seen from the 105 outside of the carriage, as best illustrated in Figures 1 and 3 of the drawings.

Having thus described the invention, what is claimed as new is:

A toy comprising front and rear cross 110 runners, side runners connecting the cross runners and having longitudinal slots near

their rear ends, a wheeled axle inserted through and slidably supported in said slots, rods secured in and adjustable through the rear runner and provided at their front ends 5 with hooks engaged around the wheeled axle, a floor secured upon the runners, a spindle mounted vertically in the floor in advance of the axle, a cage secured on the spindle above the floor, a sheave on the spindle below the floor, a pulley on the axle, 10 and a belt trained around the sheave and the pulley.

In testimony whereof I affix my signature.
JOSEPH MATUSHAK. [L.S.]
